RAILWAY CONSTRUCTION

Victor N. Wolfersberger, Mount Lebanon, Pa.

Application September 13, 1938, Serial No. 229,781

6 Claims. (Cl. 238—299)

This invention relates to railway construction and particularly to a bond or connection for anchoring a rail to associated crossties.

One of the objects of the present invention is to provide a rail-crosstie connection which is simple in construction and easily assembled during the process of laying new or replacing old sections of railroad construction and readily dismantled in repairing lines already in service.

10 Another object of the invention is to provide a rail bond which positively prevents transverse or lateral shifting or movement of the rails, the bond being devoid of spikes, bolts or any other like securing means.

15 Another object of the invention is the provision of a rail-crosstie connection so arranged and constructed that tilting forces transmitted to the rail by superimposed rolling stock are distributed throughout an appreciable area of a subjacent 20 crosstie.

25 A still further object of the invention is the provision of means fixedly associated with the rails and positioned in the horizontal plane of the crosstie to arrest creeping or longitudinal movement of the rails with respect to the crosstie.

Another object of the invention is the provision in a rail-crosstie connection of interlocking means whereby the rails are positively retained in a predetermined transverse position or relation.

30 These and numerous other objects will become apparent from the following description and from an inspection of the accompanying drawing which illustrates a form of the invention in various figures and wherein:

35 Figure 1 is a plan view illustrating a section of railroad construction embodying the present invention; the section including a crosstie, two laterally spaced rails and means for anchoring the rails to the crosstie.

40 Figure 2 is a vertical view partially in elevation and partially in section to more clearly illustrate the invention, and is taken along the lines 2—2 of Figure 1, looking in the direction of the arrows.

45 Figure 3 is a view showing a crosstie in vertical section and the associated structure in elevation and is taken along the lines 3—3 of Figure 2, looking in the direction of the arrows.

Figure 4 is a view similar to that of Figure 3 50 and illustrating a form of means associated with the construction to prevent creeping or longitudinal movement of the rails.

Figure 5 is a view taken along the lines 5—5 55 of Figure 4, looking in the direction of the arrows.

Figure 6 is a plan view somewhat similar to the structure disclosed by Figure 1 with the exception that the construction is arranged to lock two adjacent crossties together and the contiguous or associated ends of superimposed rails 5 are secured together against relative vertical or transverse movement.

Figure 7 is a view taken along the lines 7—7 of Figure 6, looking in the direction of the arrows.

Referring now in detail to the various figures 10 of the drawing and particularly to Figures 1 to 3 thereof, wherein like reference characters designate like parts, the numeral 1 indicates a section of railway construction comprising, in part, a plurality of crossties or transversely disposed rail 15 supports 2. While only one crosstie is illustrated in the accompanying drawing in the various figures under immediate consideration, it will be clearly understood that a section of railway construction comprises many of such crossties positioned a predetermined distance apart. The crosstie of the present invention is desirably shaped as an I in vertical cross section having a top horizontal flange 3 spaced vertically from a bottom correspondingly disposed flange 4. The 20 top and bottom flanges 3 and 4 are integrally joined by means of a centrally disposed upright rib or web 5. The top flange 3 presents a horizontal bearing plate for a superimposed rail, while both the top flange 3 and bottom flange 4 25 are vertically spaced means for transmitting vertical loads to the roadbed or ballast (not shown). The crossties are preferably of commercial rolled sections and, if found desirable, may assume a configuration of any contour as it 30 is not the present intention to limit the invention to the particular crosstie section illustrated.

35 As previously stated, the crosstie forms a subjacent support for transversely spaced, longitudinally extending rails 6 which are substantially of 40 conventional form and each of which comprises a head 7 and a vertical centrally disposed web 8, the latter of which terminates in lower supporting flanges 9 directed transversely of the rail on either side of the web to form a base plate 10 45 which preferably bears directly on the crosstie top flange 3.

50 The instant invention contemplates dispensing with the necessity of employing a track gauge used in replacing or repairing railway constructions so as to position the rails and successive sections in a constant transverse relation. It will, of course, be clearly understood that if the rails are not properly spaced and the space therebetween constantly maintained along the right of 55

way derailment of the rolling stock will occur as well as lateral or transverse movements being set up or created in the rolling stock, which will result in considerable damage not only to the 5 rolling stock but to the roadbed and railway construction. In accordance with the above, therefore, there has been provided a central rib 11 integrally formed with and depending from the rail 10 base plate 18 preferably in vertical alignment 10 with the rail web 8. The rib 11 is coextensive with the remaining elements of the rails and outlined by faces substantially perpendicular to one another to present a square or rectangular cross section. The crossties are, adjacent their respective 15 ends, provided with transverse grooves or recesses 12 extending longitudinally of the railway construction and forming receptacles or pockets 13 for the rail ribs 11. The recesses are desirably formed to neatly receive the rail ribs 11, and 20 in this manner any transverse movement between the rails will be eliminated or arrested. This association of rail rib and crosstie groove obviates the necessity of providing the usual bolts, spikes or like elements to retain the rails in a 25 predetermined transverse relation and, as will be understood, any tendency, created by the superimposed rolling stock, of the rails to move transversely with respect to one another will develop shear stresses in the depending ribs, and for this 30 reason the ribs need not be of such great proportion. The rail ribs not only provide a lock to prevent lateral shifting of the associated rail with respect to the subjacent crosstie but also form means for rigidifying the rail against a 35 superimposed load by increasing the over-all depth of the rail without increasing the height of the rail above the crosstie. While only a single rail rib is disclosed in the accompanying drawing and herein described, it will be clearly understood, 40 if desired, each rail may be provided with two or a series of the illustrated ribs and that such a construction is anticipated.

Due to lateral thrusts being transmitted to the rails by the rolling stock, the rails are bound or anchored to the crossties to prevent transverse 45 tilting thereof, and in order to accomplish this result the portion of the rail in the proximity of the crosstie is secured against the recited tilting by means of an integral rail plate, anchor or bond, 50 generally designated by the reference character 14. The anchor or securing means 14 is desirably formed as a unitary element having portions thereof lying above and below the crosstie top flange 3 and laterally on either side of the rail, 55 to thereby distribute any forces transmitted thereto throughout an appreciable area of the crosstie.

Each securing means is provided with a T-shaped orifice or aperture 15 to accommodate the 60 top flange 3 and web 5 of the crosstie. The aperture 15 extends transversely of the securing means and is partially defined across the upper extremity thereof by inner and outer counterpart plates 16 and 16^a respectively which bear upon a top 65 flange 3 and extend on either side of the rail transversely of the railroad construction.

Depending from adjacent the longitudinal edges of each upper plate are spaced end legs 17 substantially equal in height to the thickness of 70 the top flange 3 and closely embracing the crosstie top flange therebetween. The legs 17 desirably extend outwardly or transversely from and in the horizontal plane of the rail depending rib 11. The legs 17 terminate in inwardly or longitudinally directed arms or reentrant flanges 18

which underlie the top flange 3 in intimate relation and preferably abut the crosstie web 5. The flanges 18 extend beneath the crosstie top flange and rail substantially the full length of the securing means to connect the legs 17 of each upper plate and, therefore, cooperate with the upper plate 16 and 16^a through the legs 17 to bind the rail to the crosstie. The inner or rail adjacent extremity of each upper plate is formed of a configuration to coincide with the associated 10 contour of the rail web 8 and flanges 9, and in this manner tilting forces created in the rails are distributed across or throughout an appreciable rail and upper plate contacting area, while the same forces will be distributed in the subjacent crosstie through the reentrant flanges 18. As will be noted, the corresponding or rail adjacent extremities of the legs 17 define a longitudinally directed guideway or recess 19 which is in longitudinal alignment with the crosstie groove 20 15 and accommodates the rail depending rib 11. From the foregoing it will be noted that the rails are firmly retained in transverse alignment and securely anchored to the crossties through the medium of the securing means 14 without the 25 necessity of bolts, spikes or any like instruments.

The present invention also contemplates arresting or preventing longitudinal movement or creeping of the rails with respect to the underlying crosstie and associated securing means. By 30 referring to Figures 4 and 5, wherein an exemplified form of anti-creeping means is illustrated, there is disclosed a triangular or gusset-shaped knee brace or shear lug 20 forming a downward continuation of the rail rib 11 and abutting the 35 securing means 14. The brace 20 has its upper edge 21 scarfed or tapered, as at 22, to form, with the overlying rib 11, pockets for the reception of longitudinal welds 23. By the particular disposition of the shear lugs in the horizontal plane 40 of the crosstie it will be observed that if the rail 6 is to move longitudinally the forces will be transmitted to the crosstie through the legs 17 and reentrant flanges 18 and that no additional 45 securing means need be employed to effectively overcome any forces tending to shift the rail longitudinally. As will be understood, a knee brace may also be positioned on the opposite side of the securing means or, if desired, knee braces 50 may be oppositely positioned adjacent alternate securing means, and in this manner the rails will be prevented from creeping in either direction.

It will be observed that the illustrated construction is assembled by first threading the top flange 3 and web 5 of the crosstie through the 55 T-shaped orifice 15 of the securing means until the guideway 19 of the securing means is in longitudinal alignment with the crosstie groove 12, at which time the rail may then be threaded through 60 the correspondingly formed opening in the securing means. The shear lugs may at that time be welded in place to complete the construction.

Referring now to Figures 6 and 7, which disclose a construction arranged to lock the meeting or associated ends of the rails together and prevent relative movement therebetween either in a vertical or a transverse direction, there is illustrated, in the present embodiment, two crossties or rail supports 2^a spaced relatively close to one another and each of which comprises vertically 65 spaced horizontal top and bottom flanges 3^a and 4^a, respectively, connected by an intermediate vertical web 5^a. Superimposed or resting directly upon the crossties 2^a are adjacent extremities of rails 6^a which have their meeting edges lying 70

substantially in a vertical plane between the crossties so as to position an end of each rail in overhanging relation with the associated subjacent crosstie. The rails 6^a of the illustration under immediate consideration are substantially identical in every respect with the construction of the previously illustrated and described rail 6, and, as will be understood, depending rail ribs 11^a are positioned in correspondingly formed grooves or recesses (not shown) in the crossties to prevent lateral movement of the rails with respect to the crossties and to maintain the associated rails in longitudinal alignment and in a predetermined transverse position or relation with respect to the opposite rails of the railroad construction.

Forming a rail supporting beam spanning the crossties 2^a is a rail anchor plate or bond 14^a which, like the previously described anchor 14, is desirably formed as a single element. The securing means 14^a comprises inner and outer upper plates 16^b and 16^c respectively bearing upon the crosstie top flanges 3^a on respective sides of the rails 6^a and supporting flanges 9^a of the rails.

Extending downwardly from adjacent the transverse edges of each of the upper plates are end legs 17^a positioned in the close proximity and outwardly of the crosstie top flanges 3^a. The end legs are of a height substantially equal to the thickness of the top flanges 3^a and extend from the longitudinal edges of the securing means to the ribs 11^a of the rails to define, as in the previously described structure, a guideway for the rail ribs. Interposed between the end legs 17^a are central or intermediate legs 17^b which are of a width substantially equal to the distance between the adjacent edges of the crossties, to thereby form a spacing means to retain the crossties in a predetermined spaced relation longitudinally of the railway construction. The end legs 17^a terminate in reentrant flanges 18^a which underlie the associated portion of the top flanges and abut the corresponding crosstie webs 5^a, while the intermediate legs 17^b terminate in oppositely disposed flanges 18^b which are positioned in the close proximity and subjacent to the associated portion of the top flanges 3^a and also abut the associated crosstie webs 5^a. The flanges 18^a and 18^b extend along the entire length of the securing means to join the end and intermediate legs 17^a and 17^b respectively and to cooperate with the upper plates 16^b and 16^c to retain the crossties and superimposed rails in horizontal and vertical alignment.

It will be noted that merely an exemplified form of the invention is illustrated and described and that various alterations and amendments may be made thereto without departing from within the spirit and scope of the appended claims.

I claim:

1. In a railway construction having a rail provided with a vertical web and supporting flanges, and a subjacent crosstie having vertically spaced top and bottom flanges connected by a vertical web, the combination of a boltless securing means comprising transversely spaced upper plates bearing upon said rail flanges and crosstie top flange and abutting said rail web, end longitudinally disposed legs depending from said upper plates and embracing said top flange, reentrant flanges underlying said top flange in bearing relation therewith and abutting said crosstie web, a rib depending from said rail supporting flanges extending through aligned grooves in said se-

curing means and crosstie to prevent lateral movement of said rail, and means secured to said rib being adapted to bear against said end legs to arrest creeping of said rail.

2. In a railway construction having a rail provided with a vertical web and supporting flanges and a subjacent crosstie having vertically spaced top and bottom flanges connected by a vertical web, the combination of an integral securing means comprising counterpart plates spaced on either side of said rail and bearing upon said crosstie and rail flanges, legs depending from said plates and terminating in flanges directed toward one another and intimately associated with said crosstie top flange and web, aligned recesses in said crosstie and securing means, means extending downwardly from said rail and accupying said recesses to arrest relative transverse movement between said rail and crosstie, and a triangular gusset secured to said means and extending below said crosstie top flange to thereby engage said securing means and prevent longitudinal movement of said rail with respect to said crosstie and securing means.

3. In a railway construction having a rail provided with a vertical web and supporting flanges, and a subjacent crosstie having vertically spaced top and bottom flanges connected by a vertical web, the combination of securing means comprising inner and outer upper plates superimposed on and in bearing relation with said supporting flanges and top flanges, legs depending from longitudinal and opposite edges of each upper plate and embracing said top flange therebetween, spaced reentrant flanges extending beneath said top flange and joining the legs of said inner and outer plates, means depending from said rail and associated with said crosstie for preventing relative transverse movement therebetween, and a knee brace secured to said means and lying entirely within the horizontal plane of said crosstie for engagement with said securing means for preventing creeping of said rail.

4. In a railway construction having a rail provided with a vertical web and supporting flanges, and a subjacent crosstie having vertically spaced top and bottom flanges connected by a vertical web, the combination of a boltless securing means comprising inner and outer upper plates bearing upon said supporting flanges and top flange and abutting said rail web, legs depending from opposite longitudinal edges of each upper plate and embracing said top flange therebetween, spaced flanges extending beneath said top flange and joining the legs of said inner and outer plates, said flanges contacting said crosstie web, and a rib depending from said supporting flanges in the vertical plane of said rail web, said rib being of rectangular cross section and occupying a correspondingly formed recess in said top flange to prevent relative transverse movement between said rail and crosstie and a knee brace welded to said rib and abutting one of said flanges for arresting longitudinal movement of said rail.

5. In a railway construction having a rail provided with a vertical web and supporting flanges, and a subjacent crosstie having vertically spaced top and bottom flanges connected by a vertical web, the combination of securing means comprising inner and outer upper plates superimposed on said supporting flanges and top flange, legs depending from opposite edges of each upper plate and embracing said top flange therebetween, spaced flanges extending beneath said top flange and joining the legs of said inner and outer plates,

- a rib depending from said supporting flanges in the vertical plane of said rail web, said rib being of rectangular cross section and occupying a correspondingly formed recess in said top flange to prevent relative transverse movement between said rail and crosstie, and a knee brace welded to said rib and adapted to abut said securing means for arresting longitudinal movement of said rail with respect to said crosstie.
- 5 6. In a railway construction having a rail provided with a vertical web and supporting flanges, and a subjacent crosstie having vertically spaced top and bottom flanges connected by a vertical web, the combination of an integral securing means comprising inner and outer upper plates bearing upon said supporting flanges and top flange and abutting said rail web, longitudinally disposed legs depending from opposite edges of each upper plate and embracing said top flange therebetween, spaced flanges extending beneath said top flange and joining the legs of said inner and outer plates, said flanges contacting said crosstie web, a rib depending from said rail flanges, said rib being interposed between the legs of said inner and outer plates and occupying a recess in said top flange to prevent lateral movement between said rail and crosstie, and a gusset secured to said rib and adapted to abut said securing means for limiting longitudinal movement of said rail with respect to said crosstie.
